(57) **CLAIM**

The ornamental design for a huber safety needle, as shown and described.

DESCRIPTION

FIG. 1 is a top plan view of a huber safety needle;
 FIG. 2 is a rear elevational view thereof;
 FIG. 3 is a front elevational view thereof;
 FIG. 4 is a bottom plan view thereof; and,
 FIG. 5 is a left side elevational view thereof, the right side
 elevational view being a mirror image.
 Broken lines are for illustrating unclaimed portions of the
 article and form no part of the claimed design.

1 Claim, 4 Drawing Sheets# US D853,559 S
